UNITED STATES PATENT OFFICE.

TOM DRAKE AND ROBERT DUDLEY CARTER, OF BROADHEATH, ENGLAND, ASSIGNEES
TO LINOTYPE AND MACHINERY LIMITED, OF LONDON, ENGLAND, A LIMITED LIABILITY COMPANY OF GREAT BRITAIN.

DISTRIBUTING MECHANISM OF TYPOGRAPHICAL COMPOSING MACHINES.

1,424,887.

Specification of Letters Patent. Patented Aug. 8, 1922.

Application filed April 9, 1921. Serial No. 459,865.

To all whom it may concern:

Be it known that we, TOM DRAKE and ROBERT DUDLEY CARTER, both subjects of the King of the United Kingdom of Great Britain and Ireland, and residing at Linotype and Machinery Works, Broadheath, in the county of Chester, England, have invented new and useful Improvements in the Distributing Mechanism of Typographical Composing Machines, of which the following is a specification.

This invention relates to the distributing mechanism of typographical composing machines such as those known commercially under the trade mark "Linotype" and it has for its object so to construct that mechanism that the rate of distribution of the matrices per revolution of the distributor screws may be conveniently increased.

In the above particularized machines as ordinarily constructed, the matrices are traversed along a permuted distributor bar by three distributor screws with the convolutions of which, the matrices are caused to engage by a so-called matrix-lifter which lifts them at the rate of one per revolution of the said screws, this matrix-lifter being actuated by a single-lobed cam fast to one of the screws. The pitch of the threads of the distributor screws (usually a quarter inch) has generally corresponded with that of the bar permutations although for the purpose of dealing with matrices of more than normal thickness, it has heretofore been proposed to increase the pitch of the distributor screws to a half inch. In the use of the last mentioned screws, however, while the increase of pitch provides for an increase in the rate of traverse of the matrices along the distributor bar, the absolute rate of distribution remains unaffected, as the matrices must still be fed to the screws at the rate of one per revolution. As far as the speed of distribution is concerned, therefore, the advantage of the increased pitch is limited to an increase in the rate of traverse of the matrices along the distributor bar.

The present invention secures an increase in the absolute rate of distribution by attaining the dual result of an increase in the speed of matrix-traverse along the distributor bar and an increase of the number of

matrices engaged with that bar per revolution of the distributor screws. 55

The invention will now be described by reference to the accompanying drawings in which:—

Figure 1 is a rear elevation of sufficient of the aforesaid distributing mechanism to 60 illustrate the embodiment therein of the present invention, and

Figure 2 is a face view of the double-lobed cam employed therein.

Except as regards the hereinafter particularized parts the mechanism represented in the drawings is of the ordinary well-known construction, 1 being the distributor beam, 2 the permuted distributor bar, 3 the matrix-lifter, the bowl 4 of which is actuated by the distributor cam, the last-named being, in accordance with the present invention, of special construction as herein-after described. 5 is the distributor-box, also of ordinary construction, from which 70 matrices are successively raised by the lifter 3 on to the distributor-box rails 6 and into engagement with the distributor screws. 75

The last-named screws 7, in accordance with the present invention, are distinguished 80 from those heretofore used by having the screw threads thereon increased both as to pitch and number. The example illustrated in the drawings shows each such screw provided with two threads and in order to more 85 clearly demonstrate this feature, one of the threads, in contra-distinction to the other, has the portions of its convolutions which would otherwise be invisible, indicated by dotted lines; furthermore, the pitch of the 90 screws is increased to double that of distributor screws of ordinary construction.

With distributor screws 7 of the just-mentioned construction it is obvious that two matrices can be engaged with the screws at 95 each revolution thereof, and in order to effect such engagement it is necessary for the matrix-lifter 3 to operate twice per revolution of said screws instead of once as ordinarily. To attain this result the cam 8 100 which operates the lifter 3 is, as shown in Figure 2, provided with two lobes 9, the said cam being in known manner rigidly secured to the shaft of one of the distributor screws 7. It will be understood that there 105 are the usual two upper distributor screws

7 (only one of which is illustrated in the drawings), one on each side of the distributor bar 2, and one lower distributor screw, these being geared together and having their 5 threads inclined in accordance with their respective direction of rotation.

As, with the above named arrangement, the distributor mechanism is capable of dealing with double the number of matrices 10 per revolution of the distributor screws, it will be obvious that a rate of distribution considerably above normal may be secured although the distributor screws are being rotated at less than normal speed, and the 15 rate of traverse of the matrices along the distributor bar 2, by reason of this reduced speed of rotation, will be kept within safe and convenient limits without any risk of the matrices accumulating in the distributor 20 tor-box, although such rate of traverse may and preferably should be above normal notwithstanding the reduced speed of rotation of the screws.

Having thus described our invention, its 25 construction and mode of operation, what we claim and desire to secure by Letters Patent of the United States is as follows:—

1. Distributing mechanism such as described, having a distributor bar, and a plurality of distributor screws, characterized 30 by means for feeding a plurality of matrices

to the distributor screws during each revolution of the latter.

2. In or for the distributing mechanism of a typographical composing machine, a 35 multiple-thread distributor screw having all of its threads active during the distributing operation.

3. In the distributing mechanism of a typographical composing machine, the combination with a distributor screw having a plurality of threads, of a matrix-lifter actuating cam having a corresponding plurality of actuating surfaces. 40

4. Typographical distributing mechanism 45 including, in combination, a rotary screw formed with a plurality of threads, and means whereby a corresponding plurality of matrices may be fed to said screw at each rotation thereof.

5. Typographical distributing mechanism including, in combination, a multiple-thread screw, a reciprocating finger for feeding matrices one at a time to said screw, and means for imparting a plurality of reciprocations to said finger at each rotation of the 50 screw.

In witness whereof, we have hereunto subscribed our names.

TOM DRAKE.
ROBERT DUDLEY CARTER.
